ABRAHAM GARBEIL, OF PHILADELPHIA, PENNSYLVANIA, AND ALBERTO CIMOROSI,
OF GLASSBORO, NEW JERSEY.

TOY TORPEDO.

1,199,775.

Specification of Letters Patent.

Patented Oct. 3, 1916.

Application filed December 8, 1915. Serial No. 65,765.

To all whom it may concern:

Be it known that we, ABRAHAM GARBEIL, a citizen of the United States, residing at Philadelphia, county of Philadelphia, and 5 State of Pennsylvania, and ALBERTO CIMOROSI, a subject of the King of Italy, residing at Glassboro, county of Gloucester, and State of New Jersey, have invented certain new and useful Improvements in Toy Torpedoes, 10 of which the following is a specification.

Our invention relates to improvements in toy torpedoes, the object of the invention being to provide a torpedo which is of general spherical or oblong shape resembling a 15 marble, and which can be manufactured and sold at a reasonably low price.

A further object is to provide a toy torpedo which comprises an outer casing of two semi-spherical sections inclosing an explosive material, and having a coupling sleeve confined by the sections and operating as a container for explosive material.

With these and other objects in view, the invention consists in certain novel features 25 of construction and combinations and arrangements of parts as will be more fully hereinafter described and pointed out in the claims.

In the accompanying drawings: Figure 1 30 is a view in side elevation illustrating our improved torpedo. Fig. 2 is a view in section on the line 2—2 of Fig. 1, and Fig. 3 is a view in section on the line 3—3 of Fig. 1.

Our improved torpedo comprises two shell 35 sections 1, 1, which are preferably of paper, and preferably of semi-spherical shape.

3 represents an inner tube which is preferably of paper, and which in assembling the 40 torpedo is filled with the explosive composition illustrated by the reference numeral 4, and located within one shell section 1. The other shell section can then be readily placed over the end of the tube, and the two sections can be secured together in any approved manner. We have illustrated a strip 45 of paper which is positioned around the two shell sections 1, 1, and secured by mucilage or otherwise, and we would have it understood that any form of binder or 50 closure may be used to hold the shells together and to ornament the torpedo as desired.

While in the drawings, the tube 3 is more or less rigid, as a matter of fact in manufacture this tube when the shell sections are

forced together, will conform in shape to the inner face of the shell sections, and the explosive composition will fill all the space inside the shell sections, so that an explosion is caused when any surface of the shell 60 receives an impact.

We would have it understood that while our invention is not limited to any particular explosive composition, we preferably use gravel mixed with chlorate of potash, antimony, and sulfur.

The shape the tube will take will, of course, depend upon the strength of materials used and we consider ourselves at liberty to employ any material for the purpose.

While we have illustrated our improved torpedo as of spherical shape, we are of course, not limited to this shape, nor to the other precise details of construction, but consider ourselves at liberty to make such changes and alterations as fairly fall within the spirit and scope of the appended claims.

Having thus described our invention, what we claim as new and desire to secure by Letters Patent is:

1. A toy torpedo comprising a shell formed of two similar half sections and an explosive composition therein adapted to be exploded by a jar, said sections constituting 85 a complete inclosure for said composition and a band encircling said sections and securing the same together, substantially as described.

2. A toy torpedo comprising a shell 90 formed of two similar sections with their edges in engagement, and an explosive composition therein adapted to be exploded by a jar, said sections constituting a complete inclosure for said composition and a band 95 encircling said sections transversely of the plane of their meeting edges, and securing the same together, substantially as described.

3. As a new article of manufacture, a toy torpedo comprising two shell sections, a tube 100 inclosed by the sections and projecting across the meeting line of the sections, and an explosive composition in the tube, substantially as described.

4. As a new article of manufacture, a toy 105 torpedo comprising two semi-spherical paper shell sections, a tube within the shell sections, an explosive composition in the tube, and a binder around the shell sections securing them together, substantially as described. 110

5. As a new article of manufacture, a toy torpedo comprising two semi-spherical paper shell sections, a tube within the shell sections, an explosive composition in the tube, and a paper strip secured around the shell sections and holding them together, substantially as described.

In testimony whereof we have signed our

names to this specification in the presence of two subscribing witnesses.

ABRAHAM GARBEIL.
ALBERTO CIMOROSI.
